PUMP OR COMPRESSOR

Kenneth J. R. Cocke, Rugby, England, assignor to
General Electric Company, a corporation of
New York

Application September 3, 1935, Serial No. 39,076
In Great Britain September 14, 1934

11 Claims. (Cl. 230—206)

My invention relates to pumps or compressors and more particularly to such pumps or compressors having auxiliary pumps associated therewith.

5 It is an object of my invention to provide a compressor having an improved arrangement for supplying oil or other liquid lubricant to the working parts thereof and which requires a minimum number of moving parts.

10 Another object of my invention is to provide a compressor having an auxiliary pump utilizing the driving shaft or crank-pin of the compressor as a displacement member for pumping a fluid.

15 A further object of my invention is to provide a compressor having an improved lubricant pump of simple and rugged construction.

20 Further objects and advantages of my invention will become apparent as the following description proceeds and the features of novelty which characterize my invention will be pointed out with particularity in the claims annexed to and forming a part of this specification.

25 For a better understanding of my invention, reference may be had to the accompanying drawings in which Fig. 1 is a sectional view of a compressor embodying my invention; Fig. 2 is a sectional view on the line 2—2 of Fig. 1; Figs. 3 and 4 are views of the section shown in Fig. 2 with the cross-head slide in its extreme left and right positions respectively; Fig. 5 is a sectional view along the line 5—5 of Fig. 2; and Fig. 6 is a sectional elevation view of a compressor similar to that of Fig. 1 but having a modified arrangement of the valve parts.

30 Referring now to the drawings, I have shown a compressor comprising a cylinder block 10 secured to a frame 11, a hollow piston 12 slidably mounted in a cylinder 13 in the block 10, a driving shaft 14 journaled in a bearing 15 in the frame 11 and connected to drive the piston 12 through a crank-pin 16 and a slide 17 mounted within a cross-head 18 secured to the piston 12. A counter-weight 19 is provided on the shaft 14 to balance the compressor. The cylinder 13 is 35 closed by a cylinder head or valve box 20 secured to the block 10.

40 In accordance with my invention, I arrange the axes of the crank-pin and the cross-head slide at an angle of slightly less than 90 degrees to each other, thereby causing relative movement between the slide and crank-pin axially of the crank-pin during operation of the compressor, and I utilize this relative movement to pump liquid such as lubricant to the working 45 parts of the compressor.

Referring particularly to Fig. 2, the cross-head slide 17 is provided with a bore 21 the axis of which forms an angle of slightly less than 90 degrees with the axis of movement of the slide 17, contrary to the usual practice whereby the 5 crank-pin and slide are at right angles. The crank-pin 16 is fitted within the bore 21, and the cross-head 18 and slide 17 are thereby maintained in position with their axes intersecting the axis of the crank-pin at an angle of less than 10 90 degrees. As the shaft 14 rotates during operation of the compressor the slide 17 moves back and forth within the cross-head 18 and a reciprocating movement is imparted to the piston 12. At the same time, since one end of the 15 cross-head 18 is higher than the other, it is apparent that there must be relative movement between the slide 17 and the crank-pin 16 axially of the crank-pin. It is this relative movement which I utilize to pump lubricant or other liquid 20 to the working parts of the compressor. Fig. 3 shows the crank-pin and slide in their extreme left hand position in the cross-head, and Fig. 4 shows them in their extreme right hand position. It is readily apparent that the volume of the 25 chamber formed in the bore 21 between the cross-head and the lower end of the crank-pin 16 and designated at 22 is greater when the crank-pin is in its left hand position than when it is in its right hand position. In order to utilize this change in volume to pump lubricant, 30 I provide a port 23 affording communication between the chamber 22 and a passage 24 within the piston 12 terminating in a port 24a at the bottom of the piston. This construction can 35 clearly be seen in Figs. 1 and 5. The port 24a communicates with an inlet port 25 while the volume of the chamber 22 is increasing, that is, when the crank-pin 16 is moving from the position of Fig. 4 toward the position of Fig. 3, the 40 shaft 14 rotating from right to left as indicated by the arrow in Fig. 1. When the crank-pin 16 moves from its position in Fig. 3 to its position in Fig. 4 the port 24a communicates with an annular 45 passage 26 formed in the block 10 and surrounding the piston 12. The passage 26 communicates with an outlet connection 27 through which the lubricant may be conducted to other working parts of the mechanism, such as the compressor and motor bearings. A portion 28 of the 50 walls of the cylinder 13 completely closes the port 24a when the crank-pin 16 is in its extreme positions as indicated in Figs. 3 and 4, these positions of the crank-pin corresponding to the mid-position of the piston 12. During the op-

eration of the compressor, while the piston 12 is on the left hand side of its mid-position, lubricant from a suitable supply source, such as a sump in the bottom of the compressor casing, 5 is drawn in through an inlet conduit 29 and passes through the ports 25 and 24a to the chamber 22, and while the piston 12 is on the right hand side of its mid-position the lubricant is expelled through the passage 24 and flows into 10 the passage 26 from which it is discharged through the passage 27. The slide 17 is supplied with lubricant by grooves 30 which communicate with the port 23 at either end of a cross passage 31. The arrangement of the 15 crank-pin at an angle of less than 90 degrees to the axis of the slide and cross-head thus provides a positive pumping action which is made available for supplying lubricant to the piston 12 and the working parts of the compressor.

20 In Fig. 6 I have shown a compressor similar to that illustrated in Fig. 1, but having a modified arrangement of the intake and exhaust ports for the oil pump. The construction of the oil pump comprising the cross-head, slide and crank pin is the same as that in the modification shown in Fig. 1, and corresponding parts have been designated by the same numerals. In this arrangement separate intake and exhaust passages 32 and 33 respectively, are provided 25 in the compressor piston 12. These passages are arranged side by side in the piston 12 and both communicate with port 23 and hence with the chamber 22. The intake passage 32 has a port 34 at the bottom of the piston which communicates with the port 25 of the oil intake pipe 29 during the intake stroke of the oil pump. The passage 33 is provided with a port 35 at the top of the piston which communicates with an exhaust port 36 during the exhaust stroke of the oil pump. During the operation of the compressor oil is drawn into the chamber 22 from the inlet conduit 29 through ports 25 and 34, 30 passage 32, and port 23. The oil is expelled from the chamber 22 through port 23, passage 33, ports 35 and 36 to a passage 37, whereby it is conducted to the other working parts of the compressor. When the passage 32 is in communication with the intake conduit 29, the passage 33 is closed by the walls of the cylinder 13, and when the passage 33 is in communication with the outlet passage 37, the passage 32 is closed by the wall of cylinder 13. The oil which is pumped to the working parts of the mechanism through the passage 37 is returned 35 through a passage 38 and enters an annular passage 39 formed in the wall of cylinder 13 about the piston 12 and after flowing around the piston the oil is discharged from the passage 39 into an outlet conduit 40 through which it returns to the sump or other source of oil. In order to insure adequate lubrication of the piston 12, two annular grooves 41 and 42 are formed in the piston, these grooves communicate with the annular groove 39 when the piston 12 is near its extreme positions, and are thereby kept filled 40 with the oil. This arrangement of the compressor and oil pump provides adequate lubrication 45 of the compressor piston and an ample supply of oil for lubricating the other working parts of the mechanism.

50 It is readily apparent, therefore, that I have provided an auxiliary pump for compressors which is arranged to supply lubricant or other fluid to the working parts of the compressor and which is effective in operation and of extremely 55 rugged and simple construction.

While I have shown a particular embodiment of my invention I do not desire my invention to be limited to the specific construction shown and described, and I intend in the appended claims to cover all modifications within the spirit 5 and scope of my invention.

What I claim is new and desire to secure by Letters Patent of the United States is:

1. A fluid compressor including in combination a cylinder block having a cylinder therein, mechanism for compressing gaseous fluid in said cylinder, mechanism including a driving shaft having a pin rigidly mounted thereon for driving said compressing mechanism, and mechanism utilizing said pin as a displacement member for pumping fluid. 10

2. A fluid compressor including in combination a cylinder block having a cylinder therein, a piston arranged in said cylinder, a driving shaft, mechanism including a crank-pin rigidly mounted on said shaft for driving said piston to compress gaseous fluid in said cylinder, and auxiliary pumping mechanism utilizing said crank-pin as a displacement member for pumping fluid. 20

25 3. A fluid compressor comprising in combination a cylinder block, a piston slidably mounted in said block, a rotatable driving shaft for said piston, a crank-pin rigidly mounted on said shaft, mechanism including a cross-head and slide connecting said crank-pin and said piston for reciprocating said piston, and auxiliary pumping mechanism utilizing said crank-pin as a displacement member for supplying lubricant to said compressor. 30

35 4. A fluid compressor comprising in combination a cylinder block, a piston slidably mounted in said block, a rotatable driving shaft for said piston, a crank-pin mounted on said shaft, mechanism including a slide connecting said crank-pin and said piston for reciprocating said piston, the angle between the axis of said slide and the axis of said crank-pin being less than 90 degrees, and mechanism utilizing relative movement between said slide and said crank-pin for pumping fluid. 40

45 5. A fluid compressor comprising in combination a cylinder block, a piston slidably mounted in said block, a rotatable driving shaft for said piston, a crank pin mounted on said shaft, a cross-head secured to said piston, mechanism including a slide mounted in said cross-head and engaging said crank pin for reciprocating said piston, the angle between the direction of movement of said slide in said cross-head and the axis of said crank-pin being less than 90 degrees, and mechanism utilizing relative movement between said slide and said crank-pin for pumping fluid. 50

55 6. A fluid compressor comprising in combination a cylinder block, a piston slidably mounted in said block, a rotatable driving shaft for said piston, a crank-pin rigidly mounted on said shaft, mechanism including a slide having a bore therein engaging said crank-pin for connecting said shaft and said piston to reciprocate said piston, said crank-pin being movable axially in said bore, and mechanism utilizing the axial movement of said crank-pin in said bore for pumping fluid. 60

65 7. A fluid compressor comprising in combination a cylinder block, a piston slidably mounted in said block, a rotatable driving shaft for said piston, a crank-pin rigidly mounted on said shaft, mechanism connecting said piston and said 70 75

crank pin for driving said piston, and mechanism utilizing said crank-pin as a displacement member and including a passage in said piston for pumping fluid.

5 8. A fluid compressor comprising in combination a cylinder block, a piston slidably mounted in said block, a rotatable driving shaft for said piston, a crank-pin rigidly mounted on said shaft, mechanism including a cross-head on said 10 piston and a slide engaging said crank pin for reciprocating said piston, said crank pin being movable axially in said slide, mechanism including a port in said slide and a passage in said piston and utilizing said crank pin as a displacement member for pumping fluid.

15 9. A fluid compressor comprising in combination a cylinder block having a cylinder therein, a piston slidably mounted in said cylinder, a rotatable driving shaft for said piston, a crank- 20 pin rigidly mounted on said shaft, mechanism including a slide engaging said crank-pin and said piston for reciprocating said piston, and mechanism utilizing said crank-pin as a displacement member and including a passage in said 25 piston and inlet and outlet ports in said cylinder for pumping fluid.

10. A fluid compressor comprising in combination a cylinder block having a cylinder therein, a piston slidably mounted in said block, a rotatable driving shaft for said piston, a crank-pin rigidly mounted on said shaft, a cross-head 5 secured to said piston, mechanism including a slide engaging said crank pin and said cross-head for reciprocating said piston, and mechanism utilizing said crank-pin as a displacement member and including intake and exhaust 10 passages in said piston for pumping fluid.

11. A fluid compressor comprising in combination a cylinder block, a piston slidably mounted in said block, a rotatable driving shaft for said piston, a crank-pin mounted on said shaft, a 15 cross-head secured to said piston, mechanism including a slide mounted in said cross-head and engaging said crank pin for reciprocating said piston, the angle between the direction of movement of said slide in said cross-head and 20 the axis of said crank pin being less than 90 degrees, and mechanism utilizing relative movement between said slide and said crank-pin and including a passage in said piston and inlet and 25 outlet ports in said block for pumping fluid.

KENNETH J. R. COCKE.
